DESIGN FOR A CAB BODY OR THE LIKE

Robert L. Allen and Jacob P. Gardner,
Battle Creek, Mich.

Application July 16, 1945, Serial No. 120,730

Term of patent 14 years

(Cl. D14—3)

To all whom it may concern:

Be it known that we, Robert L. Allen and Jacob P. Gardner, citizens of the United States, residing at Battle Creek, in the county of Calhoun and State of Michigan, have invented a new, original, and ornamental Design for a Cab Body or the like, of which the following is a specification, reference being had to the accompanying drawing, forming part thereof.

Figure 3 shows a side elevational view. The other side is the same with the door hinged at the rear; and

We claim:

The ornamental design for a cab body or the like, substantially as shown and described.

ROBERT L. ALLEN.
JACOB P. GARDNER.
